RAIL CLAMP FOR MACHINE TOOLS

Filed Sept. 29, 1948

UNITED STATES PATENT OFFICE

2,638,659

RAIL CLAMP FOR MACHINE TOOLS

John M. Walter, Cincinnati, Ohio, assignor to The
G. A. Gray Company, Cincinnati, Ohio, a cor-
poration of Ohio

Application September 29, 1948, Serial No. 51,737

6 Claims. (Cl. 29—1)

1

This invention relates to a rail clamp for machine tools, and more particularly to a clamp for clamping the rail with respect to the columns in such machine tools as planers, boring mills and the like.

It has been conventional to provide clamping means to clamp the rail to the columns in a desired position of adjustment, but the clamping means has heretofore always been so arranged that the clamping effect was normal to the direction of movement of the rail on the columns, and no lateral clamping effect had ever been attained.

It is an object of my present invention, therefore, to provide a novel clamping arrangement in which a lateral clamping effect is obtained in addition to the normal or conventional clamping effect.

It is a further object of my invention therefore to achieve this lateral clamping effect by a relatively simple modification of existing clamping means, whereby the clamping means of the present invention, although more effective than any known heretofore, will be very little more expensive than the present types of clamping means.

These and other objects of my invention which will be pointed out hereinafter, or which will become apparent to one skilled in the art as the description proceeds, I accomplish by that certain construction and arrangement of parts of which I shall now describe an exemplary embodiment. Reference is made to the drawings forming a part hereof, and in which:

Figure 1 is a horizontal cross-sectional view through the columns of a planer or the like, showing the relation of the rail thereto and illustrating the clamping means.

Figure 2 is a detailed view of one of the clamps in plan with parts in cross-section.

Figure 3 is a fragmentary vertical cross-sectional view taken on the line 3—3 of Figure 1.

Figure 4 is a fragmentary cross-sectional view taken on the line 4—4 of Figure 3.

I shall first describe so much of the structure of a conventional planer columns and rail and conventional means as is necessary to an understanding of the present invention. Thus, the columns of the machine tool are indicated at 10 and the rail arranged for travel thereon is indicated at 11. Relative movement between the rail 11 and columns 10 is accomplished on the cooperating ways 10a and 11a. A portion of the rail indicated generally at 12 enters into a recess between the columns 10 and contains the actuati-

ing mechanism for the rail clamping means. As best seen in Figure 3 there is provided a motor 13 and a speed reducer 14 which drives a threaded shaft 15. The screw 15 engages a nut 16 having a T-shaped head 16a fitting within a boss 17 of the cross-bar 18 so as to be non-rotative with respect to the bar 18. The nut is held in place in the boss 17 by means of a washer 19 engaging over the shaft 15, pressed against the boss 17 by means of a helical spring 20 which bears at its other end against a portion of the rail casting 11b. The end of the shaft 15 as at 15a has a bearing in the portion 11b.

As the shaft 15 rotates the nut 16 will travel along it toward the right or left as seen in Figures 3 and 4, and movement of the nut will carry with it the cross bar 18. At each end the cross bar 18 engages a lever 21 pivoted in the rail as at 22 so that the rotation of the screw 15 produces rocking of the levers 21 about their pivots 22. Each of the levers 21 is provided with a recess 23 within which is pivotally mounted as at 24 a rocking equalizing member 25 having contact elements 26 and 27. The members 26 and 27 engage respectively the push rods 28 and 29 which actuate the clamping members to be described hereinafter. By virtue of the mounting of the member 25 an equal thrust is exerted on the members 28 and 29 when the lever 21 is rocked in a counterclockwise direction, as seen in Figure 3.

Referring now to Figure 1, the push rods 28 are shown as engaging respectively the ends of the levers 30, the other ends of which as at 31 engage the shoulders 32 on the columns. The levers 30 are secured to the rail by means of the screws 33 which are threaded into the rail 11. The heads of these screws 33 have a spherical underside at 34 cooperating with a spherical counterbore in the lever 30 and the bore through the lever 30 is oversize so that the lever 30 may rock slightly with respect to its bolt 33, thus the bolt 33, cooperating with the spherical counterbore in the lever 30 provides a ball and socket action. When the motor 13 is energized causing the screw 15 to rotate rocking the lever 21 in a counter-clockwise direction so as to exert a thrust on the push rods 28 (this thrust on the levers 30 being in an upward direction as seen in Figure 1), each of the levers 30 is rocked about its bolt and socket joint so as to produce a downward thrust of the edge 31 against the shoulder 32, thus clamping the rail to the columns. The clamping system thus far described is in all respects conventional.

The clamping means of my invention are thus seen at the upper portion of Figure 1 which in the particular instance illustrated are actuated by the lower push rods 29. While the levers 30 of the conventional type may be considered as levers of the first class, the clamping members 40, according to my invention, may be considered as levers of the second class. These levers have the portions 41 engaging the shoulders 42 of the columns, and they are also provided with the bolts 43 having the ball and socket action 44, all as described above in connection with the levers 30. The bolts 43 however instead of being threaded into the rail are threaded into the wedge blocks 45. These wedge blocks are disposed in a space between each column and the rail and are constrained to travel up and down with the rail by the guide plates 46. As illustrated these wedge blocks have a straight side 45a arranged to coact with the straight surface on the column, and they have the angular surface 45b arranged to cooperate with the angular surface 42b on the rail. Thus, when pressure is exerted by the push rods 29 the levers 40 are rocked about their fulcrum at 41 and draw the wedge blocks 45 upwardly. By the coaction of the surfaces 45a and 45b a lateral clamping effect is also attained and, therefore, any lateral play is eliminated.

In the drawings I have shown an arrangement which has proven satisfactory where 2 of the usual 4 clamps are according to my invention. It will be clear that there may be installations where only a single pair of clamps according to my invention may be required, or it may be desirable in a 4-clamp arrangements to have all 4 of the clamps according to my invention.

It will also be clear that numerous modifications may be made in details of construction without departing from the spirit of my invention. I therefore do not intend to be limited otherwise than as set forth in the claims which follow.

Having now fully described my invention, what I claim as new and desire to secure by Letters Patent is:

1. In a machine tool having columns and a rail arranged to travel thereon by means of cooperating ways, there being spaces between said columns and rail longitudinally of the direction of relative movement of said columns and rail, said spaces having converging side walls in a direction normal thereto, a pair of clamps for clamping said rail with respect to said columns and each comprising a lever of the second class having its fulcrum on one of said columns and the force being applied from said rail, and the load comprising a wedge block disposed in each said space and secured to one of said levers between said fulcrum and said force, said wedge blocks, when force is applied to said levers, engaging said converging walls to exert a lateral clamping action between said columns and rail.

2. In a machine tool having columns and a rail arranged to travel thereon by means of cooperating ways, a pair of clamps for clamping said rail with respect to said columns, each clamp comprising a wedge block between one of said columns and the rail, means secured to said rail and engaging said blocks to constrain said blocks to move with said rail, a lever secured to each of said blocks and having a portion engageable with one of said columns, said wedge blocks adapted to exert a wedging action between said columns and said rail upon actuation of said levers.

3. In a machine tool having columns and a rail arranged to travel thereon by means of cooperating ways, a pair of clamps for clamping said rail with respect to said columns, each clamp comprising a wedge block between one of said columns and the rail, means secured to said rail and engaging said blocks to constrain said blocks to move with said rail, a lever of the second class secured to each of said blocks and having its fulcrum on one of said columns, the force being applied to each of said levers from the rail, and said wedge blocks constituting the loads and exerting a lateral clamping action between said columns and said rail upon actuation of said levers.

4. In a machine tool having columns and a rail arranged to travel thereon by means of cooperating ways, a first pair of clamps adjacent the bottom and at the rear of said rail for clamping said rail with respect to said columns, each clamp comprising a wedge block between one of said columns and the rail, means secured to said rail and engaging said blocks to constrain said blocks to move with said rail, a lever secured to each of said blocks and having a portion engageable with one of said columns, said wedge blocks adapted to exert a wedging action between said columns and said rail upon actuation of said levers; and an additional pair of clamps adjacent the top and at the front of said rail to secure said rail in cooperation with said first pair of clamps.

5. A machine tool according to claim 2, wherein means are provided for equalizing the actuating forces on said levers.

6. A machine tool according to claim 4, wherein means are provided for equalizing the actuating forces on the levers of said first pair of clamps, means are provided for equalizing the forces on the clamps of said additional pair, and means are provided for equalizing the forces applied to said means.
